UNITED STATES PATENT OFFICE.

EDGAR J. BLOOM, OF TIFFIN, OHIO.

GOLF-GREEN CUP.

Application filed November 1, 1927. Serial No. 230,271.

This invention relates to golf green cups and more specifically to improvements in the construction of golf cups or liners of the type adapted to support the staff of a signal flag or marker.

It is customary, in a golf course, to employ a liner or cup for the hole in the putting green. These cups are provided to support the earth forming the side walls of the hole and are frequently constructed with some means for supporting the signal flag or marker shaft, which ordinarily, is removably retained by a member rigidly associated with the cup.

In the average golf course it is the practice to change the location of the cup or liner when the sod adjacent the mouth opening becomes worn and it is, therefore, important that a golf cup be constructed so that it may be readily inserted into and removed from a cylindrical hole, in the green, without the use of any special equipment and without material injury to the earth surrounding the hole.

It is also important that the cup or hole liner be so constructed as to assure its effective anchorage in the earth as any movement of the cup initiated through the vibration of the flag or signal shaft will cause the earth to be dislodged, the cylindrical form of a hole to be distorted and the walls of the hole deformed so that they will be rendered incapable of being refilled with earth in a satisfactory manner.

In the golf cup and signal supporting structures heretofore constructed the advantage of having the cup rigidly anchored in the ground has been lost sight of except perhaps in that type of cup which is provided with a feed screw or spiral formed at the bottom of the cup. In this type of cup, however, there resides the disadvantage of maintaining the vertical alignment of the cup when it is inserted into the earth and also the impracticability of refilling the hole after a cup of this type is removed therefrom. It has been the uniform practice to support the signal flag or marker by a plate or web which is disposed transverse the medial axis of the cup either at its bottom or intermediate its ends. This member is usually apertured to receive the shaft or is formed with an extended boss having an opening therein to receive one end of the marker shaft. In the exercise of this prac-

tice the strain imposed by the wind pressure against the flag is transmitted to the side walls of the cup and in turn is borne by the earth surrounding the cup which frequently becomes distorted and permits the cup to be loosened in the hole.

In the practice of my invention I have provided a signal supporting member associated with the cup, the supporting member, however, being formed with a coaxial anchor post which is of proper form and proportion to provide per se a support for the marker. In addition, I have constructed a golf cup so that it may be readily inserted into the hole or removed therefrom without causing the earth to be dislodged or without necessitating the use of special tools or any particular dexterity of the attendant changing or repositioning the golf green cup.

In the accompanying drawing, Figure 1 is a vertical section of a golf green cup embodying my invention, the cup being shown in place in a golf green hole.

Figure 2 is a plan view of the cup illustrated in Figure 1,

Figure 3 is a transverse section taken on a plane indicated by the line 3—3 in Figure 1,

Figure 4 is a vertical section of a cup similar to that shown in Figure 1, but illustrating a structural modification,

Figure 5 is a transverse section taken on the plane indicated by the line 5—5 in Figure 4,

Figure 6 is a plan view of an alternate form of a golf ball retaining plate,

Figure 7 is a vertical section of the cup illustrating a modified form of anchor post.

Figure 8 is a vertical section of a cup illustrating an alternate type of anchor post and the support therefor.

Referring to the drawing the golf cup illustrated in Figures 1, 2 and 4, comprises a cylindrical tube section or golf hole liner 10 having a spider 11 formed within the cup intermediate its ends and preferably disposed slightly below the center of the cup. The spider 11, in the present embodiment is formed with a central hub section 12, the upper portion of which is recessed at 13 to receive the shaft 14 of the signal flag. The lower portion of this hub is constructed with an aligned depending boss which terminates with a diverging spike or anchor post 15. As illustrated the spike 15 is cruciform in

transverse section being formed with divergent flanges or ribs which are pyramidically terminated.

The hub 12 is joined to the cylindrical tube section by a plurality of webs 16, the upper edges 17 of which lie in a common plane at right angles to the medial axis of the hub 12. Within the cup 10 there is a disc 18 which is provided to retain the golf balls played into the cup, one of which is indicated herein by the dotted circle 19. The disc 18 is constructed with an axial boss 20 extending from its opposite faces and each boss is formed with a beaded outer edge 21 to afford a finger grip for the removal of the disc. The disc 18 is supported upon the outer edges 16^a of the webs 16 and is centralized within the cup by the engagement of a vertically disposed pilot boss 22, formed in the hub 12, and an aperture 23 which extends through the boss 20 and disc 18. The upper faces of the webs 16^a are rounded in order to preclude the adhesion of extraneous matter between the disc 18 and these bearing surfaces. The webs 16 are formed with notches 24, adjacent the pilot boss 22, the width and depth of these notches being suitably proportioned to afford a clearance for the depending portion of the boss 20.

The recess 13, or signal flag socket, is preferably extended to a depth substantially equal to one-half the total length of the hub and spike sections 12 and 15 respectively, and the mouth 25 of the hub is chamfered to facilitate insertion of the shaft of the flag.

Referring now to Figures 4 and 5, the embodiment herein illustrated, comprises a structure similar to that shown in Figure 1 but formed of separate cup and signal supporting units in order to accommodate manufacturing practices. The spider 26 in this embodiment is secured to the cup 27 by rivets 28, or other suitable means, which unite the walls of the cup 27 with flanges 29 formed in the terminating ends of the webs 30. The upper edges of these webs are formed with rounded ribs 30^a which lie in a common plane and support a golf ball retaining disc 31. The webs 30 are reinforced near their upper edges by transversely disposed flanges 32 integrally formed with the spider 26, the webs 30 and the flanges 29. The disc in the instant case is constructed with a single boss 33, which is vertically disposed with the upper face of the disc, and is adapted to be centralized within the cup by engagement of the boss 34 with a concentric opening 35 in the boss 33.

As shown in Figure 6, a modified form of disc is illustrated which comprises an annular plate centrally apertured at 36 and provided with perforations 37 which serve

as a finger cup to facilitate the removal of the plate from the cup 27.

In both forms of my invention, the disc 18 is supported on the relatively narrow edges of the web of the spider and is positioned by the concentric hub bearing. This arrangement facilitates the removal of extraneous matter between the disc and the flanges which may be accomplished by twisting or oscillating the plate upon its seat 75 about the central pilot bearing.

In Figure 7 I have illustrated an anchor post in which the webs 16 are extended and merge with the divergent flanges or ribs of the anchor post or spike 15.

The anchor post shown in Figure 8 comprises a separable shaft 40 preferably made of wood which is supported in the opening 13 by virtue of the tapered walls thereof. These spikes may be made in variable lengths to accommodate suitable anchorage in various kinds of soil.

In the type of cup having inadequate anchorage in the earth, the hole, in which the cup is seated, frequently becomes enlarged or so distorted that the sod adjacent the top edge of the cup may be driven inwardly or compressed thus causing the earth to overhang the mouth of the opening or to recede therefrom. Frequently, too, the hole will become bell-mouthed or the unsupported earth will crumble away from the edge of the hole causing a ledge to be formed between the earth and the top edge of the cup upon which the golf ball may be deflected. Under these conditions a well played ball may be arrested in its course or if the hole has become bell-mouthed a ball less accurately played may roll into the cup when in fact the fortuitous "hole" should not be credited to the player.

In the practice of my invention, I have found the initial position of the cup in the earth may be maintained even though the structure has been subjected to the radial thrusts initiated by the wind pressure against the signal flag or target. The rigidity of the earth surrounding the cup and the stability of the structure when positioned is effectuated by the allocation of the spider relative to the vertical axis of the cup and by the proportion of the length of the spike or anchor post 15 and the length of the cup.

As will be seen in Figure 4 when a hole A is cut in the sod of a golf green incident the positioning of the structure, the cylindrical tube section of the cup may be inserted in the hole approximately one-third of its length before the end of the spike 15 will come into contact with the floor or bottom of the hole A. By virtue of the pilot bearing thus afforded the axial alignment of the cup will be retained upon further insertion of the structure within the hole even though

some light extraneous matter in the earth, should tend to deflect the course of the spike as it was forced into position.

When the cup is seated, as illustrated in Figure 1, and the flag is in place, the radial thrusts imposed by the whipping of the flag in the wind, will be borne by the hub and resisted by earth surrounding the vertical wall of the cup and lower edge 38 and by the spike or anchor post 15, the combined areas of which will afford sufficient contact with the earth to assure the adequate rigidity of the cup.

When the cup is rigidly supported in the earth the possibility of the hole becoming enlarged will be obviated and furthermore the contour of the sod forming the rim of the hole may be preserved in the form most advantageous to the success of the game.

Although the foregoing description is necessarily of detailed character, in order that the invention may be completely set forth, it is to be understood that the specific terminology is not intended to be restrictive or confining and that the various re-arrangements of parts and modifications of structural detail may be resorted to without departing from the spirit or scope of the invention as herein claimed.

I claim:

1. A golf green cup comprising a tubular body, a signal supporting section united therewith and a separable golf ball retaining plate, said signal supporting section having an anchor post the major portion of which extends beyond one end of the cup.

2. A golf green cup comprising a tubular body having a spider disposed within the said body intermediately its ends, said spider formed with a plurality of webs rigidly connected to the inner wall of said tubular

body and radiating from an apertured hub portion, a golf ball retaining plate, and an anchor post integral with said hub portion and extending beyond said tubular portion. 45

3. A golf cup comprising a tubular body, a spider axially disposed therein having a centrally apertured hub section, a plurality of webs radiating therefrom and connecting said hub and the inner wall of said tubular body, a separable golf ball retaining plate having centrally disposed apertured bosses extending from its opposite faces, grooves in the upper face of said webs to admit the said boss of the ball retaining plate, and an anchor post extending from one end of the tubular body section. 50 55

4. A golf green cup comprising a tubular body, a spider axially disposed therein and united thereto, said spider having a centrally apertured hub portion formed with oppositely extended bosses one of which is adapted to position a golf ball retaining plate, the other formed with a plurality of divergent ribs extended beyond the cup. 60 65

5. A golf cup comprising a tubular body, a spider axially disposed therein having a centrally apertured hub section, a plurality of webs radiating therefrom and connecting said hub and the inner wall of said tubular body, a removable golf ball retaining plate having centrally disposed apertured bosses extending from its opposite faces each of said bosses being grooved adjacent its ends, grooves in the upper face of said webs to admit the said boss of the ball retaining plate and an anchor post extending from one end of the tubular body section. 70 75

In testimony whereof I hereunto affix my signature this 29th day of October, 1927.

EDGAR J. BLOOM.
